UNITED STATES PATENT OFFICE.

HYLA FREDERICK MAYNES, OF GAINES, PENNSYLVANIA

AMUSEMENT APPARATUS.

1,918,200.

Specification of Letters Patent. Patented Mar. 6, 1917.

Application filed December 19, 1916. Serial No. 137,763.

To all whom it may concern:

Be it known that I, HYLA FREDERICK MAYNES, a citizen of the United States, and resident of Gaines, in the county of Tioga and State of Pennsylvania, have invented certain new and useful Improvements in Amusement Apparatus; and I do hereby declare the following to be a full, clear, and exact description of the invention, such as will enable others skilled in the art to which it appertains to make and use the same.

This invention relates to amusement apparatus, and more particularly to the type of apparatus wherein the particular amusement afforded is intended to be of an unexpected sort.

For the purpose mentioned use is made of a conveyer and a starting chamber at one end of the conveyer, the starting chamber having a collapsible support for one or more persons to occupy, and means for collapsing the support in the direction of the conveyer to cause the person or persons sitting on the seat member thereof to be discharged from the seat member onto the conveyer to travel along the same.

A construction of this general nature is disclosed in U. S. Letters Patent No. 1,058,615, April 8, 1913, issued to me. The structure there disclosed provides, in combination with a starting chamber of the kind above indicated, a conveyer comprising a fixed incline down which a person slides by gravity following his ejection from the seat member of the support when the support is collapsed.

The present invention involves the provision of a generally improved conveyer for coöperation with a suitable starting chamber, this conveyer being of the moving type, and preferably including an endless conveyer belt which is power-driven and so guided and controlled as to traverse any desired path while transporting a passenger from the starting chamber along such path and toward the exit end of the machine. Although in the arrangement shown the path of the conveyer is downwardly inclined it may, obviously, be upwardly inclined or horizontal if desired.

The present invention further involves, and some of the claims are specifically directed to, the provision of a generally improved starting chamber, including an improved collapsible support for always discharging a passenger onto the conveyer

safely, smoothly and swiftly, and improved means for collapsing the support operated from outside the chamber.

These and the various other features of the invention will be clearly understood from the following description, when taken in connection with the accompanying drawings showing a preferred embodiment, of which—

Figure 1 is a side elevation showing the apparatus supported on suitable framework of tubular construction; Fig. 2 is a top plan of the parts shown in Fig. 1, the roof of the starting chamber being partially broken away; Fig. 3 is an enlarged detail view, showing the starting chamber, collapsible support and the upper end portion of the conveyer in vertical section; Fig. 4 is a view similar to Fig. 3 showing the support collapsed; Fig. 5 is an enlarged detail view showing the operating lever and other working parts of Fig. 1 reset to collapse the support as shown in Fig. 4; Fig. 6 is a fragmentary perspective view showing the collapsible support and certain parts operating therewith; Figs. 7 and 8 are enlarged detail views showing the method of mounting the anti-friction rollers forming parts of the collapsible support; Figs. 9, 10 and 11 are enlarged views showing details of construction of an undulating slideway which forms part of the conveyer; and Figs. 12 and 13 are enlarged views showing the method of mounting the transporting and wear belts constituting an endless conveyer belt which also forms a part of the conveyer, Fig. 13 being a sectional view on the line 13—13 of Fig. 12.

Referring to Figs. 1 and 2, it is preliminarily explained that one or more persons, having ascended to the platform on which the starting chamber 14 is supported, enter the chamber by way of the doorway 15 and seat themselves on a bench-like support 16, anticipating, in theory at least, some other form of amusement than a sudden collapse of the seat and a discharge therefrom onto an endless transporting belt or carpet 17, for subsequent exit from the apparatus by way of the apron 18.

The support 16 is collapsed, after the sliding door 19 has been moved to close the doorway 15, by an attendant swinging a lever 20 to the left of Fig. 1; the carpet 17 being preferably continuously driven in the direction of the arrows.

As shown best in Fig. 6, the collapsible support comprises the following parts. A seat-block 22, which may be constructed of wood, serves as the rear wall of the starting chamber 14, and is pivoted at indicated at 23 to a crossbar of the supporting framework. The seat-back is provided at its lower end with a pair of hinge members 24 to which are pivotally attached a pair of links 25. Each link 25 is pivoted to a link 26 by means of a cross-rod 27 and each link 26 is in turn pivoted to a link 28 by a cross-rod 29. The forward ends of links 28 are joined by a cross-rod 30, this rod forming a part 15 of the means for suspending the extreme forward end of the support 16 in both positions of the latter. A swing-bar 31 and a chain 32 are attached at their lower ends to the oppositely projecting terminal portions 20 of rod 30; the upper end of the swing-bar being pivoted to a side wall 14^a of the starting chamber 14 (see also Fig. 5) and the upper end of the chain being attached to the supporting framework beyond the far side 25 of the starting chamber (see also Fig. 4).

Intermediate their ends links 26 are pivotally mounted on brackets 33 by means of a cross-rod 34 journaled in the brackets and fixedly carrying the links 26. Fixed also to this rod 34 is an offset arm 35 connected by a link 36 with an arm 37 secured on shaft 38 formed integral with the operating handle 20.

Slightly spaced, parallel, transversely arranged anti-friction rollers 39 coöperate with the links 25, 26 and 28 in building up the collapsible support 16, so that the support when collapsed as shown in Fig. 4, will always safely, smoothly and swiftly 40 eject from the starting chamber 14 the person or persons within the same. Certain of these rollers 39, as indicated in Fig. 6, are hollow, so as also to house the cross-rods 27, 34, 29 and 30. Each of the other rollers 39 45 is journaled at its opposite ends in the two links between which it extends. The rollers 39 which extend between the links 25 and between the links 26 are mounted on these links by means of journal plates 40 shown on an enlarged scale in Figs. 7 and 8.

Referring to Fig. 3, a collapsible support 16 is thus provided which comprises a seat-back 22 pivoted for movement about a fixed point A, a seat-member B pivotally connected to the seat-back, a seat-riser C pivotally connected to the seat-member B, and also pivoted for movement about a fixed point D, a floor member E pivotally connected to the seat-riser C, and a suspending 55 means (the swing-bar 31 and chain 32) pivotally connected to the floor member and also pivoted for movement about a fixed point F. As a result of this construction it will be seen that the collapsible support not 60 only constitutes a collapsible seat structure

but also the floor and back wall of the starting chamber. Considering the said suspending means as a single lever, the collapsible support, it will be noted, consists of three lever elements and two link elements alternately arranged and all positively connected, so that solely as the result of a partial rotation of the central element, a lever, the side riser C, the support is collapsed into an elongated slide or reformed into a seat-structure, according to the direction of rotation of said central element. Thus, when the operating handle 20 is moved to the left of Fig. 1, the support 16 is collapsed, and when this handle is moved to the right the collapsed support is reformed into a seating structure.

Due to the slight inclination of the seat riser C, the support 16 is collapsed, not by springs or other permanently connected agents to be subsequently contended with when the seating structure is reformed, but by the mere weight of the occupants of the starting chamber; the work of the attendant being no more than to release the handle 20 from the catch 20^a. When the starting chamber has been thus emptied of its occupants, the attendant swings the operating handle 20 toward the right of Fig. 1, for engagement with the catch 20^a; thereby turning the shaft 38 and causing, through arm 37, link 36 and arm 35, a rocking of the cross-rod 34 so as to reform the collapsible support into a seating structure which also provides the floor and back wall of the starting chamber.

A panel or door 41 of some suitably rigid material is fixedly carried by the operating shaft 38, so that when the operating handle 20 is actuated to rock the shaft 34 and thus collapse the support 16, the door 41 is swung up and out over the conveyer. The door 41 is normally closed as shown in Figs. 3 and 6, to conceal from those seating themselves on the support within the starting chamber, not only the nature of the conveyer onto which they are to be precipitated, but also the fact of the existence of such a conveyer. The door in its open position and the support in its collapsed condition, and their relation to the upper end of the conveyer where the transporting carpet 17 commences its downward travel, are all shown very clearly in Fig. 4.

The conveyer of which this transporting carpet 17 forms a part comprises, as shown best in Figs. 1 and 2, and in Figs. 9 to 13, a fixed slideway or guideway 42, having an undulating upper surface and a general line of extension which is descending, a pair of endless conveyer chains 43 each guided over idler sprockets 44 and 44^a and over a driving sprocket 45 controlled by a clutch 46, and a pair of wide endless belts, one of which is the transporting carpet 17 and the other a

canvas wear belt 49, attached to the conveyer chains to travel with them and thus be guided relative to the upper surface of the slideway 42.

5 As shown in Figs. 9, 10 and 11, the slideway 42 comprises a pair of inclined supporting beams 42^a slung on the shafts 44^a of the sprockets 44. Across these beams are laid transverse floor planks 47. The floor planking may be secured in place by means of the parallel strips 48, which may be of leather or of polished metal to act as anti-friction agents relative to the canvas wear-belt 49.

10 15 As shown in Figs. 12 and 13, the endless transporting carpet belt 17 and the endless canvas wear-belt 49 are connected to each other and to the two conveyer chains by cross-bands 50, which may be of spring-steel 20 covered with canvas, arranged at suitable intervals.

25 The endless conveyer thus comprised of the chains, belts and cross-bands, is so constructed, as by forming the belts or cross-bands or both of a fabric of slightly elastic weave, that a sufficient amount of give is provided to permit the weight of the person being transported down the conveyer to sag the carpet belt 17 between the sprockets 44 30 and thus cause the carpet belt to follow the dips in the undulating upper surface of the slideway 42. In this connection, sheet-like members 51 are provided in overlapping arrangement and anchored at their rear ends. 35 As these members are shown in Figs. 9 and 11, they are arranged irregularly and so as to irregularly overlap laterally as well as longitudinally of the slideway. When thus arranged, they impart a rolling as well as a 40 pitching effect to the moving carpet. Whether regularly or irregularly arranged, however, these members 51, when anchored at their ends so as to overlap the anchored rear ends of the members in advance, are of 45 equal value in one respect. They permit the canvas wear-belt 49 to pass smoothly down the incline without rubbing over unevenly applied planks 47. These members 51 may be of leather, and the leather may be of 50 sufficient thickness and stiffness, when the members are irregularly arranged, to give such pitching and rolling effect to persons traveling on the transporting carpet 17. Or these members may be made of spring steel 55 or the like, to increase the rolling and pitching effect. The carpet may be of a plain or mottled green to suggest a sea-way.

60 The operation of the apparatus should be clear from the foregoing. It may, however, be particularly pointed out that when the support 16 of Fig. 3 is collapsed to form the ejection slide shown in Fig. 4, the axes of all the anti-friction rollers 39 lie in a single inclined plane, due to the manner in which the 65 links 25, 26 and 28 are formed and inter-

connected. As a result, the occupants of the starting chamber are ejected onto the transporting carpet 17 from an ejection slide totally free from bumps. Also, as the result of the provision of these anti-friction rollers 70 39, only a very slight inclination from the horizontal of said ejection slide is necessary. While the departure of a patron from the starting chamber may be speedily accomplished, as soon as the door 19 is closed, so 75 as to take care of different groups of patrons in quick succession at the starting chamber, the ride down the slideway 42 may be prolonged very considerably over the time required for the descent of a gravity incline 80 of equal length, for the reason that the transporting carpet 17 may be moved at any uniform speed, or even at intermittently variable speeds, as desired.

85 The whole apparatus may be suitably housed, as in a tent, or by canvas walls hung on and over the supporting framework. In any event, it is preferable to form an inclined tunnel extending from end to end of the slideway 42, so as to conceal the presence 90 of the conveyer and especially its relation to the starting chamber 14. The tunnel walls may be so arranged as to maintain the tunnel in darkness from the starting chamber to a point near the apron 18 thus to increase 95 the startling effect of the sudden collapse of the support 16; and it will be noted from Fig. 1 that the design of the supporting framework is such as to include members 52 for facilitating the creation of such a tunnel. 100

105 The presence of the apron 18 is desirable because it insures that a person transported toward the exit end of the machine by the carpet 17 will not be injured by the passage of the carpet over the roller arranged between the driving sprockets 45; and if this apron be dispensed with it is desirable to station an attendant adjacent to the exit end of the apparatus to help those on the carpet 17 to leave the same at the lower end of the 110 conveyer.

115 It is particularly to be understood that even in the embodiment of the invention above described the slideway 42 need not be inclined downwardly relative to the starting chamber. It is obvious, for example, that a conveyer including a power-driven transporting belt like the endless carpet 17 may be so guided and controlled as to descend or ascend, or keep to a level course, or even follow the uphill and downdale path of a roller-coaster or switchback, or turn or twist as desired, while transporting a passenger from the starting chamber to the exit end of the machine. It is of course to be 125 further understood that the improved collapsible support forming a part of the present invention may with considerable advantage be employed also in connection with any slideway or downwardly inclined guide- 130

way constituting a fixed conveyer, for transporting a passenger toward the exit end of the apparatus after his ejection from the collapsible support; such a fixed conveyer for example, as an immovable chute similar to the gravity slide shown in said Letters Patent No. 1,058,615.

I claim:

1. An amusement apparatus of the kind described, comprising a conveyer, a seat-member adjacent to the conveyer, a plurality of rollers mounted on the seat-member, and means operable to move the seat-member to cause a person seated thereon to slide over the rollers and off the seat-member toward the conveyer.
2. An amusement apparatus of the kind described, comprising a conveyer, a seat-member adjacent to the conveyer, a floor member associated with the seat-member, anti-friction members revolubly mounted on the seat-member and on the floor member, and means operable to move the seat-member to cause a person to slide by gravity over the anti-friction members off the seat-member onto the floor member and thence off the floor member onto the conveyer.
3. An amusement apparatus of the kind described, comprising a conveyer, a collapsible support adjacent to the conveyer and including a seat-member, a seat-riser and a floor member, and means for collapsing the support into an elongated slide inclined toward the conveyer, the seat-member, seat-riser and floor member being each formed of side frames and revolubly mounted parallel cylindrical members carried by the side frames to facilitate the ejection of a person toward the conveyer from the support when collapsed.
4. An amusement apparatus of the kind described, comprising a conveyer, a tiltable floor adjacent to the conveyer, a tiltable seat-member above the floor and pivotally connected thereto, and means for simultaneously tilting the floor and the seat-member to form an ejecting slide whereby a person on the seat-member is discharged by gravity onto the floor and thence onto the conveyer.
5. An amusement apparatus of the kind described, comprising a conveyer, a tiltable floor member adjacent to the conveyer, a tiltable seat-riser pivotally connected to the rear portion of the floor member, a tiltable seat-member pivotally connected to the upper portion of the riser, and means for simultaneously tilting all these tiltable parts to reform them into an ejecting slide directed toward the conveyer.
6. In an amusement apparatus of the kind described, a conveyer, and a collapsible support adjacent to the conveyer, the collapsible support comprising pivotally connected back, seat, seat-riser, floor and floor-suspension members, the seat-riser member being fixedly pivoted intermediate its ends, whereby a rotation of the seat-riser-member collapses the support into a slide for ejecting a person on the support and depositing such person on the conveyer by gravity.
7. In an amusement apparatus of the kind described, a conveyer, and a collapsible support adjacent to the conveyer, the collapsible support comprising pivotally connected back, seat, seat-riser, floor and floor-suspension members, the seat-riser member being fixedly pivoted intermediate its ends and being sufficiently inclined from the vertical to permit the weight of a person on the seat-member to tend to rock said seat-riser member on its said fixed pivot, thus to tilt all the members so that the seat, seat-riser and floor members combine to form an ejection slide directed toward the conveyer, means for restraining pivotal movement of the seat-riser member, and means for manually releasing said restraining means.
8. In an amusement apparatus of the kind described, a collapsible support adapted when collapsed to eject a person therefrom, and a conveyer arranged to receive the person so ejected, the conveyer including a slideway having an undulating surface arranged relative to a predetermined general line of extension of the conveyer.
9. In an amusement apparatus of the kind described, a collapsible support adapted when collapsed to eject a person therefrom, a conveyer arranged to receive the person so ejected, the conveyer including an endless conveyer belt, means for driving said belt, and guiding means for the belt to cause it to traverse a predetermined path away from the collapsible support.
10. In an amusement apparatus of the kind described, a collapsible support adapted when collapsed to eject a person therefrom, a conveyer arranged to receive the person so ejected, the conveyer including a fixed guideway having an undulating surface, and an endless conveyer belt arranged and driven to traverse a downward path overlying the fixed slideway and of sufficient flexibility to follow the undulations of its surface.
11. In an amusement apparatus of the kind described, a conveyer including a fixed guideway having curved surfaces, a flexible conveyer carpet, and means for moving the carpet along the guideway, the carpet being yieldably mounted on said means so that the weight of a person on the carpet during its travel along the guideway causes the carpet to follow the curved surfaces of the guideway.
12. In an amusement apparatus of the kind described, a conveyer including a fixed guideway having curved surfaces, a flexible conveyer carpet, means for moving the car-

pet along the guideway, the carpet being yieldably mounted on said means so that the weight of a person on the carpet during its travel along the guideway causes the carpet to follow the curved surfaces of the guideway, and a plurality of irregularly arranged elastic elements anchored above the guideway and under the conveyer carpet.

13. In an amusement apparatus of the kind described, a conveyer including a fixed guideway having curved surfaces, an endless conveyer carpet, means for moving the carpet along the guideway, the carpet being yieldably mounted on said means so that the weight of a person on the carpet during its travel along the guideway causes the carpet to follow the curved surfaces of the guideway, a plurality of elastic elements anchored above the guideway and under the conveyer carpet, and a wear-belt moving with the conveyer carpet along the guideway and interposed between the elastic elements and the conveyer carpet.

14. In an amusement apparatus of the kind described, a conveyer including a fixed guideway, a flexible conveyer belt, means for moving the conveyer belt along the guideway, and a plurality of overlapping arranged sheet-like elements interposed between the guideway and the conveyer belt and fixed relative to the conveyer belt.

15. In an amusement apparatus of the kind described, a conveyer including a fixed guideway, a flexible conveyer belt, means for moving the conveyer belt along the guideway, and a plurality of overlappingly and irregularly arranged elastic sheet-like elements interposed between the guideway

and the conveyer belt and anchored to the guideway.

16. In an amusement apparatus of the kind described, a conveyer including a fixed guideway, a flexible conveyer belt, and means for moving the conveyer belt along the guideway, the conveyer belt including an endless outer transporting member, an endless inner wear member, a pair of endless conveyer chains arranged and guided for travel at opposite sides of said endless inner and outer members, and a plurality of spaced cross-bands secured at their opposite ends to the two conveyer chains and attached at their median portions to the two endless members.

17. In an amusement apparatus of the kind described, a conveyer including a fixed guideway, a flexible conveyer belt and means for moving the conveyer belt along the guideway, the conveyer belt including an endless outer transporting member, an endless inner wear member, a pair of endless conveyer chains arranged and guided for travel at opposite sides of said inner and outer members, and a plurality of spaced cross-bands interposed between said inner and outer members and secured thereto and to the two endless chains.

18. In an amusement apparatus of the kind described, a collapsible support adapted when collapsed to eject a person therefrom, and a conveyer arranged to receive the person so ejected, the conveyer including a fixed guideway having an undulating surface.

In testimony whereof I affix my signature. 75
HYLA FREDERICK MAYNES.

It is hereby certified that in Letters Patent No. 1,218,200, granted March 6, 1917, upon the application of Hyla Frederick Maynes, of Gaines, Pennsylvania, for an improvement in "Amusement Apparatus," errors appear in the printed specification requiring correction as follows: Page 1, line 89, for the numeral "12" read 13; page 5, line 28, claim 14, for the word "overlapping" read *overlappingly*; and that the said Letters Patent should be read with these corrections therein that the same may conform to the record of the case in the Patent Office.

Signed and sealed this 12th day of February, A. D., 1918.

[SEAL.]

J. T. NEWTON,
Commissioner of Patents.

Cl. 104—111.
